UNITED STATES PATENT OFFICE.

HENRY DE SMITH, OF ROCHESTER, NEW YORK, ASSIGNOR TO M. D. KNOWLTON COMPANY, OF ROCHESTER, NEW YORK, A CORPORATION OF NEW YORK.

FINGER-GUARD FOR BOX-COVERING AND SIMILAR MACHINES.

1,330,850.

Specification of Letters Patent.

Patented Feb. 17, 1920.

Application filed July 14, 1916. Serial No. 109,281.

To all whom it may concern:

Be it known that I, HENRY DE SMITH, a citizen of the United States, and resident of Rochester, in the county of Monroe and

5 State of New York, have invented certain new and useful Improvements in Finger-Guards for Box-Covering and Similar Machines, of which the following is a specification.

10 This invention relates to finger guards, and has for its object to provide an improved guard which is especially designed for use in combination with the cutting mechanism of a box-covering machine, but 15 as will hereinafter appear the improved finger guard may be used in various other relations.

The invention is illustrated in the accompanying drawings, in which—

Figure 1 is a side elevation of a portion 20 of a box-covering machine, involving the use of the improved finger guard with the cutting mechanism;

Fig. 2 is an enlarged front elevation of the cutting mechanism, the finger guard 25 and its actuating mechanism; and

Fig. 3 is an enlarged side elevation, partly in section, of the cutting mechanism and the finger guard showing in full lines the position which the parts assume when 30 the movable knife is in its raised position and showing in dotted lines the position which the parts assume when the movable knife is in its lowered position.

Similar reference characters indicate like 35 parts in the several figures of the drawings.

As above stated, the finger guard is especially designed for use in combination with the cutting mechanism of a box-covering machine, and therefore it has been 40 illustrated in the drawings in this relation. The box-covering machine shown in the drawings is of a well known type and need not be herein described in detail. It will be sufficient for the present purpose to note 45 the frame A of the box-covering machine, which carries a holder B for the box-form carrier. The holder B is mounted for pivotal movements with respect to the frame A and also for longitudinal sliding

50 movements, so that it may be readily adjusted to bring the box-form carrier C, which it carries, into proper relation relative to the cutting mechanism to suit requirements. The web of material with 55 which the box is covered, is shown at S.

Before the web S reaches the box-form carrier C, it passes through the cutting mechanism, denoted generally by the reference character D.

The box-form carrier C is rotated in the usual manner from the shaft a carried by the holder B, and when it is desired to cut the web S, the upper movable frame b of the cutting mechanism is caused to descend to cut the web by reason of the coöperation between the knife c carried by such movable frame and the knife d carried by a lower stationary frame e. The upper movable frame b is made to descend by depressing a treadle (not shown) operatively connected with the link f. The link f is thus pulled downwardly to set in rotation a cam shaft carrying a cam which controls the movement of a rod g. The cam and cam shaft just referred to are not shown in the drawings, but at a point during the rotation of said cam the rod g is permitted to descend, thus swinging a rock arm h about its pivotal connection i. The rock arm h is provided with a series of teeth j which mesh with a corresponding series of teeth k associated with a rock shaft l. The rock shaft l is operatively connected with the upper movable frame b, and it is therefore obvious that when the rod g is permitted to lower, the upper movable frame b will descend by gravity, by reason of the mechanism just described, which is interposed between the rod g and said movable frame b. When the rod g is again lifted, the movable knife 75 frame b is raised and again assumes its normal position shown in the drawings.

The structure so far described constitutes the well-known parts of a box-covering machine, such for example, as disclosed in Letters Patent No. 1,037,154, granted August 27, 1912. The finger guard constituting the present invention is associated with the cutting mechanism D and operatively connected with the upper movable frame b so as to be actuated by the movements of this frame.

In its preferred form, the finger guard comprises a bar which is disposed substantially parallel with the lower stationary knife d, and which is mounted to move in a path just above such lower knife. This bar is operatively connected with the upper movable frame of the cutting mechanism in such manner that as the upper knife descends, 105

the said bar will move outwardly over the lower knife so that if the operator's fingers happen to be in such a position that they would be injured, if not removed, the moving bar constituting the finger guard moves the operator's fingers out of the path of the descending movable knife. In order to prevent injury to the operator's fingers, in the event that the moving bar or finger guard 10 forces the operator's fingers against the lower knife, the finger guard is yieldingly mounted so that it will move upwardly and do no harm to the operator's fingers, if caught between the lower knife and the 15 finger guard.

The above mentioned bar, which constitutes the finger guard proper, is shown at 1 (Fig. 2). It is supported at each end upon a shoulder 2 carried by a stud 3, which in 20 turn is mounted in a head 4 that is rigidly secured to a sliding rod 5 which extends toward the rear of the machine and is slidably mounted in a bracket 6 rigidly secured to the lower knife frame *e*. It will be understood that these parts are duplicated at 25 each side of the machine, and therefore the bar 1 is so mounted as to be capable of moving in a path over the lower stationary knife *d* by reason of the sliding engagement between the rods 5 and the brackets 6.

The bar 1 is yieldingly held against the shoulders 2 on the studs 3 by means of a coil spring 7 mounted upon each stud. Each of 35 these springs re-acts at its upper end against a washer or other abutment 8, and at its lower end against the extremity of the bar 1. The bar 1 is therefore yieldingly held in its lowermost position, but upon meeting an 40 obstruction, such as the operator's fingers, is capable of a limited upward movement.

The parts so far described so support the bar 1 that when it moves in its predetermined path it will just clear the upper edge of the lower knife *d*.

45 Each of the heads 4 is operatively connected by means of a link 9 with the upper movable knife frame *b*. As clearly shown in the drawings, each link 9 is pivoted at its upper end to the upper movable frame *b*, as 50 at 10, and its lower end is pivotally associated with the corresponding head 4. The pivotal connection between each head 4 and the corresponding link 9 may be effected by means of a pin 11 inserted in the head 4 and 55 through an opening in the link, and this pin may also serve to lock the stud 3 in position, as clearly shown in Fig. 2, for the pin may be made to pass through a transverse opening in the stud as shown at 12.

60 It will now be noted that when the upper movable frame *b* descends, the links 9 acting upon the heads 4 move the sliding rods 5 outwardly and cause the bar 1 interconnecting the two heads 4 to move outwardly

over the upper edge of the lower knife *d*. 65 The position which the parts assume after the upper movable frame reaches its lowermost position is clearly shown in Fig. 3 in dotted lines. If the operator's fingers happen to be in a dangerous position as the upper knife descends, the finger guard or bar 1 in moving to the dotted line position will 70 force the operator's fingers out of the path of the descending knife. If the finger guard tends to force the operator's fingers against 75 the back edge of the lower knife, the finger guard will yield and move upwardly, thus eliminating any danger of the finger guard crushing the operator's fingers against the stationary knife. When the upper movable 80 frame *b* rises to its normal position, the other parts return to their normal positions in which the finger guard lies just behind the lower stationary knife.

After a sheet is cut, it is necessary for the 85 operator to reach between the knives to grasp the forward edge of the sheet to draw the same forwardly. The normal position of the finger guard should therefore be such that it does not interfere with the operator 90 grasping the forward edge of the sheet, as just described. When the operator so reaches between the knives, if the cutting mechanism be accidentally tripped, the finger guard will move forwardly and pass over the lower 95 knife to remove the operator's fingers from the path of the descending upper knife.

I am of course aware that guards of the general type herein described for removing the operator's hand or fingers from the path 100 of a moving work-performing element are not broadly new, but the finger guard herein disclosed is associated in a novel manner with the operating parts and presents such patentable features as are covered in the 105 accompanying claims.

Although the finger guard has been illustrated and described in connection with the cutting mechanism of a box-covering machine, it will now be obvious that it is not 110 limited to such use, but may be used in various machines where there is danger of the operator becoming injured by the work-performing element, and where conditions are such that the finger guard and its 115 actuating parts may be associated with the work-performing element in a somewhat similar manner to that shown in the accompanying drawings.

What I claim is:—

1. In a machine of the kind described, the combination with an oscillatory part thereof carrying a work-performing element, and a stationary part, of a finger guard slidably mounted on said stationary part to travel in 125 a horizontal path intersecting the path of the work-performing element, and connections between said oscillatory part of the

machine and the finger guard whereby movement of the former actuates the latter.

2. In a machine of the kind described, the combination with a stationary cutter and a 5 movable cutter, of a finger guard slidably mounted on the stationary part of the machine to move in a rectilinear path across the cutting edge of the stationary cutter, and a link connecting the movable cutter 10 with the guard whereby the movements of the former will actuate the latter.

3. In a machine of the kind described, the combination of a stationary knife frame, a movable knife frame pivotally associated 15 therewith, a finger guard slidably mounted on the stationary knife frame to travel in a horizontal path between said frames, and a link connecting the movable knife frame with the finger guard whereby movements 20 of the former actuate the latter.

4. In a machine of the kind described, the combination with an upper oscillatory knife element and a lower stationary knife element, of a finger guard movable in a path 25 over said lower knife element, means to actuate said finger guard, and means for yieldingly holding the finger guard in its lowermost position, said means being designed to permit the finger guard to rise in 30 the event of the operator's finger becoming caught between the lower knife element and the finger guard.

5. In a machine of the kind described, the combination with a stationary lower frame carrying a work-performing element and an 35 upper movable frame pivotally associated with the lower frame and also carrying a work-performing element, of a pair of brackets carried by said lower frame, a longitudinally sliding rod mounted in each 40 of said brackets, a finger guard yieldingly carried by said rods, and connections between the upper movable frame and the finger guard whereby movement of the former causes the finger guard to move in a 45 horizontal path over the work-performing element of the lower frame.

6. In a machine of the kind described, the combination with a stationary knife frame, of a movable frame pivotally associated 50 therewith, a finger guard slidably mounted on the stationary knife frame for movement in a horizontal path between said frames, and means connecting the movable knife frame with the finger guard, whereby the 55 movements of the former actuate the latter.

Signed at Rochester, in the county of Monroe, and State of New York, this 10th day of July, A. D. 1916.

HENRY DE SMITH.
